US0D1059132S

(12) **United States Design Patent** (10) **Patent No.:** **US D1,059,132 S**
(45) **Date of Patent:** **** Jan. 28, 2025**

(54) **FLIP PICKLE JAR**

(71) Applicant: **Yangzhou New coordinate Household Products Co., LTD**, Baoying County, Jiangsu Province (CN)

(72) Inventor: **Quan Xu**, Jiangsu Province (CN)

(73) Assignee: **Yangzhou New coordinate Household Products Co., LTD**, Baoying County (CN)

(**) Term: **15 Years**

(21) Appl. No.: **29/874,550**

(22) Filed: **Apr. 21, 2023**

(51) LOC (15) Cl. **09-02**

(52) U.S. Cl. **D7/612**

(57) **CLAIM**

The ornamental design for a flip pickle jar, as shown and described.

DESCRIPTION

FIG. 1 is a front elevational view of a flip pickle jar showing my new design;

FIG. 2 is a left side elevational view thereof;

FIG. 3 is a rear elevational view thereof;

FIG. 4 is a right side elevational view thereof;

FIG. 5 is a bottom plan view thereof;

FIG. 6 is a top plan view thereof;

FIG. 7 is a perspective view thereof; and,

(Continued)

FIG. 8 is another perspective view thereof.
The broken lines in the drawings depict portions of the flip
pickle jar that form no part of the claimed design.

1 Claim, 8 Drawing Sheets
